Attorney

UNITED STATES PATENT OFFICE.

HENRY F. BERBIG, OF DULUTH, MINNESOTA.

BEDSTEAD.

Application filed January 31, 1924. Serial No. 689,659.

To all whom it may concern:

Be it known that I, HENRY F. BERBIG, a citizen of the United States, residing at Duluth, in the county of St. Louis and State of Minnesota, have invented certain new and useful Improvements in Bedsteads, of which the following is a specification, reference being had therein to the accompanying drawing.

10 This invention relates to portable foldable bedsteads; the principal object of the invention being to produce as compact and practical a device of this character as possible, together with one that may be most conveniently set up or knocked down.

15 Other objects and advantages of the invention will appear in the further description thereof.

20 Referring now to the accompanying drawing, forming part of this application, and in which like reference characters indicate like parts:

25 Figure 1 is a fragmental vertical sectional view through the bedstead as it appears set up;

Figure 2 is a horizontal sectional view on the line 2—2, Figure 1;

30 Figure 3 is an enlarged fragmental perspective view of one of the corners of the bedstead; and

Figure 4 is a vertical section through the bedstead when knocked down and housed or assembled for transportation or storage.

35 The ends of the bedstead are preferably of combination wood and metal fabrication, they each being rectangular in shape and in the form of a receptacle. The one herein-after referred to as the head of the bed is somewhat deeper than the one at the opposite end referred to as the foot, each being composed of a four sided wooden frame like structure the ends of which are indicated at 1 and the top and bottom at 2 and 3 respectively, and each of which is covered upon one major side thereof with a sheet metal cover 4 overlapping the edges of the wooden frame on all sides as indicated at 5, said covers forming the sides of the receptacle when the bedstead is knocked down and assembled for shipment or storage.

40 The inner upper corner 6 of each wooden end piece is cut-away and the overlapping edge 5 of the sheet metal cover 4 extends into the cut-away portions 6, and are turned inwardly in spiral form as indicated at 7 to provide a hinge-like pivotal connection for

the bed stocks 8. Each of these latter are provided with metal end clips 9 projecting therefrom and curved inwardly as at 10 for interlocking engagement with the spirally curved portions 7 of the overlapping metal ends 5, and, as is readily seen, this interlocking engagement is only possible of accomplishment by a vertical sliding motion, that is to say the stocks when removed or applied to the ends of the bedstead must be moved vertically.

45 The stocks 8 of the bed are made in two halves, pivotally united by preferably a pair of hinges 11, dividing each stock into two equal parts, both ends of which are applied to the ends of the bed in like manner. The stocks being thus divided and pivotally united centrally, may be adjusted to the ends of the bed when partly jack-knifed, and subsequently forced inwardly in respect to the bed to properly space the ends thereof, which process it is evident will have the desired effect of pulling taut the springs 16 within the bedstead. These springs are 50 preferably of any well known linked wire type, so that they will readily fold up into as small a space as possible, and upon the sides thereof are connected with the stocks of the bedstead preferably by means of suitable eyelets 12 permanently attached at intervals to the side of the spring, said eyelets being slidable and removably mounted upon the upstanding pintles 13 mounted within the vertically elongated cut-out 55 notches 14 upon the inner face of the stocks, and for ordinary purposes it has been found that about four of such connections are necessary for the proper lateral support of the springs.

60 It will be noted that this provides a novel means of attachment of the springs to the stocks of the bedstead, the object of which is to avoid lateral sagging thereof, which is so objectionable in the ordinary cot or common bedstead where the springs are attached to the stocks; it being apparent that as a weight is applied to or from the springs the sides thereof may readily move vertically.

65 Longitudinally of the inside of the head and foot of the bed and securely attached to the metal walls thereof are small angle bars 15, they being spaced from the bottoms 3 of the receptacles sufficiently to permit of 70 the stocks 8 when folded being placed within the receptacles as shown in Figure 4 and

thus leaving also sufficient space above them and the tops 2 of the receptacles into which the springs 16 may be conveniently housed. These angle bars are provided with a series of suitable holes into which the springs of the bedstead may be attached, as illustrated at 17, and which attachment I prefer to accomplish in the head of the bedstead by means of suitable contractile springs 18, though it is not deemed essential that such springs be used at the foot of the bedstead, but may be if desired.

When the two halves of the receptacle formed by the union of the head and foot of the bedstead are assembled as in Figure 4 they may be held together by a common hook and eye attachment as illustrated at 19, and suitable handles of any desired construction such as of leather or the like indicated at 20 may be permanently attached thereto.

In the four uppermost corners of the head and foot of the bedstead I have formed rectangularly shaped holes indicated at 21, they being for the double purpose of providing a socket for posts of a canopy top for the bedstead when in use, or as a means for attaching the folded receptacle to another object, such as the running board of an automobile or the like.

From the foregoing it is evident that I have devised an exceedingly simple, com-

pact and convenient form of portable folding bedstead.

Having thus described my invention, what I claim and desire to secure by Letters Patent, is:

1. A folding bedstead comprising a two-part separable receptacle forming the head and foot of the bed, and foldable bed stocks for cooperative engagement with the receptacles, said stocks being foldable only outwardly, and springs permanently attached to the head and foot of the bed and vertically removably attached to the stocks for normally holding the four sides of the bed together. 40

2. The combination with a folding bedstead comprising a separable receptacle forming the head and foot of the bed and having vertically removable foldable sides 50 therein, of a spring for said bed permanently attached inwardly of the end receptacles and below the uppermost edge of the sides when installed therein; said side members being foldable within the end receptacles 55 when separated therefrom beneath the springs, substantially as and for the purpose described.

In testimony whereof I hereunto affix my signature.

HENRY F. BERBIG.
